(57) **CLAIM**

The ornamental design for a sliding sleeve and sliding rod of stair tread measuring ruler, as shown and described.

DESCRIPTION

FIG. 1 is a front view of a sliding sleeve and sliding rod of stair tread measuring ruler, showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front perspective view thereof;

FIG. 8 is a rear perspective view thereof;

FIG. 9 is a front view showing the sliding sleeve and sliding rod of stair tread measuring ruler in 1st configuration of use;

FIG. 10 is a front view showing the sliding sleeve and sliding rod of stair tread measuring ruler in 2nd configuration of use;

FIG. 11 is a front view showing the sliding sleeve and sliding rod of stair tread measuring ruler in 3rd configuration of use;

FIG. 12 is a front view showing the sliding sleeve and sliding rod of stair tread measuring ruler in 4th configuration of use;

FIG. 13 is a front view showing the sliding sleeve and sliding rod of stair tread measuring ruler in 5th configuration of use; and,

FIG. 14 is an enlarged view of detail 14 in FIG. 8.

All the broken lines in the drawings depict portions of sliding sleeve and sliding rod of stair tread measuring ruler that form no part of the claimed design.

1 Claim, 10 Drawing Sheets
